UNITED STATES PATENT OFFICE.

JOHN BERGSTEN, OF TAFT, CALIFORNIA.

ELEVATOR.

Application filed December 2, 1921. Serial No. 519,472.

To all whom it may concern:

Be it known that I, JOHN BERGSTEN, a citizen of the United States, residing at Taft, in the county of Kern and State of California, have invented certain new and useful Improvements in Elevators, of which the following is a specification.

This invention relates to elevators for raising and lowering rods, tubing, well casings, and the like.

An object of the present invention is the provision of a positive lock to hold the elevator in closed position, when a tool or other article is being raised or lowered.

15 A further object of the invention is the provision of means for retaining the elevator in open position to permit ready insertion of a tool or other article.

The locking mechanism is provided with 20 operating means normally retained in locked position by means of a spring and adapted to be retained in open position when the elevator is opened against the tension of the spring.

25 In the accompanying drawings, I have shown one embodiment of the invention. In this showing:

Figure 1 is a front elevation,

Figure 2 is a vertical sectional view,

30 Figure 3 is a horizontal sectional view on line 3—3 of Figure 1, showing the device in closed position, and,

Figure 4 is a similar view showing the device in open position.

35 Referring to the drawings, the reference numeral 1 designates the body portion of the elevator which is provided with a longitudinal slot or passage 2. This slot is intersected by a lateral recess 3, extending from one side 40 to a point adjacent the opposite side. The recess is open at the rear, as designated at 4, and the portion immediately in front of the recess is closed by a wall 5. A gripping member 6 is pivotally mounted on a pin 7, arranged in the recess and this gripping member is provided with a cut-out portion 8, which is adapted to aline with the passage 2 when in closed position. The cut-out portion is provided with jaws 9 and 10, arranged at each side.

45 A locking member 11 is arranged in the rear of the wall 5, the locking member being inserted from the side through an opening normally covered by a plate 12. As 50 shown, the locking member is hollow and is adapted to receive a spring 13, one end of

which bears against the plate 12 to normally project the locking member to the position shown in Figure 3 of the drawings. The rear face of the locking member is provided with a lug 14 adapted to be received in a forked end of a lever 15, which is pivotally mounted in the recess 3 on a pin 16. The rear end of this lever extends through the opening 4 and forms a handle 16.

The rear of the body portion is provided with a cut-out portion 17, and a pin 18 is arranged therein. As shown, the pin is provided with an enlargement 19, forming a plunger. A threaded plug 20 normally 65 closes the opening, and a spring 21 is arranged between the plug and the plunger 19. The threaded plug is provided with a longitudinal opening for the reception of the rear end of the pin, forming a guide. 70 The other end of the pin projects through wall 22 and engages the lever 15.

Suitable trunnions 23 may be arranged on each side of the body portion, and these trunnions are adapted to be received in bearings 24 formed on the lower ends of arms 25 of a support which may be of the usual type.

In operation, a rod, tubing or well casing A is retained in the elevator against vertical 85 displacement by the flange B, formed at the junction of two sections of the drill rod or other tool. The tool is prevented from lateral displacement by locking member 11, which retains the gripping device in closed 90 position. When the tool is to be removed from the casing, the locking member is retracted against the tension of spring 13 by means of the lever 15 and the gripping member is turned to the position shown in Figure 4 of the drawings, permitting the tool to be withdrawn. The jaw 9, engaging the locking member, will retain the parts in this position against the tension of the spring to permit a new tool to be inserted. 100 It will be apparent that when a rod, tubing or well casing is withdrawn from the elevator, the elevator thus remains in position to receive a new tool.

The pin 18, bearing against the lever 16 105 also places the spring 21 under tension when the device is in open position and insures proper closing of the locking member when desired.

It is to be understood that the form of the 110 invention herewith shown and described is to be taken as a preferred example of the

same, and that various changes in the shape, size, and arrangement of parts may be resorted to without departing from the spirit of the invention or the scope of the subjoined claims.

Having thus described my invention, I claim:

1. An elevator comprising a body portion having a vertical passage and a lateral recess, a gripping member pivotally mounted in said recess, said gripping member being provided with a cut-out portion adapted to aline with said passage, and a locking device comprising a laterally movable bar adapted to retain said gripping member in open or closed position.
2. An elevator comprising a body portion having a vertical passage and a lateral recess, a gripping member pivotally mounted therein, said gripping member being provided with a cut-cut portion, a locking device comprising a laterally movable bar adapted to retain said gripping member in open or closed position, and a spring to retain said gripping bar in operative position.
3. An elevator comprising a body portion having a vertical passage and a lateral re-

cess, a gripping member pivotally mounted therein, said gripping member being provided with a cut-out portion, a spring 30 pressed locking member mounted in said recess and normally engaging said gripping member to retain it in either of two positions, and a pivoted lever engaging said locking member.

4. An elevator comprising a body portion having a vertical passage and a lateral recess, a gripping member pivotally mounted therein, said gripping member being provided with a cut-out portion, a spring 40 pressed locking member mounted in said recess and normally engaging said gripping member to retain it in either of two positions, a pivoted lever engaging said locking member, and a spring pressed pin engaging 45 said lever to normally maintain said locking member in operative position.

In testimony whereof I affix my signature in presence of two witnesses.

JOHN BERGSTEN.
